UNITED STATES PATENT OFFICE.

WILLIAM ALLEN BEAMER, OF MOUNT VERNON, OHIO.

PIE CUTTER AND CRIMPER.

No. 831,208.

Specification of Letters Patent.

Patented Sept. 18, 1906.

Application filed May 5, 1906. Serial No. 315,387.

To all whom it may concern:

Be it known that I, WILLIAM ALLEN BEAMER, a citizen of the United States, residing at Mount Vernon, in the county of Knox and State of Ohio, have invented a new and useful 5 Pie Cutter and Crimper, of which the following is a specification.

This invention relates to means for crimping and compressing the upper crust of a pie 10 upon the lower crust and trimming said crusts to the size of the plate.

The principal object is to provide an exceedingly simple and novel device, which may be expeditiously fitted to pie-plates of 15 different diameters and will effect both the crimping and trimming of the pie in a single operation.

The preferred embodiment of the invention is illustrated in the accompanying drawings, wherein—

Figure 1 is a top plan view of the device. Fig. 2 is a vertical sectional view therethrough, showing the same applied to a pie; and Fig. 3 is a detail sectional view on the line 3 3 of Fig. 25 1. Fig. 4 is a cross-section on the line 4 4 of Fig. 1.

Similar reference-numerals designate corresponding parts in all the figures of the drawings.

The device is in the form of an expansile and contractile ring composed of angularly disposed annular flanges. One of these flanges 4 is substantially horizontally disposed and constitutes a compressing-ring. 30 It is corrugated, as shown at 5, and has its end portions 6 slidably overlapped. The corrugations of said end portions adjustably interfit or interlock, as shown in Fig. 3. The other flange 7 is vertically disposed and is integrally with the crimping-ring, said flange 7 depending from the outer edge of the crimping-ring 4 and constituting a cutting element. Its end portions are also overlapped. A thumb-receiving ring or handle 8 is carried 40 by the outer end of the device, and a finger-receiving holder or handle 9 is carried by an intermediate portion of the device, being disposed adjacent to the overlapped ends. The two handle elements are so related that the 45 thumb may be placed in one, and two of the fingers of the same hand in the other. These handle elements are preferably formed of looped sheet metal riveted, as shown at 10, to the ring.

In using the device the same is held in one hand by the handles 8 and 9 and can therefore be readily expanded or contracted to the diameter of the pie to be operated upon. As already stated, the corrugations of the overlapped portions interlock, and thus serve to 5 maintain the device fixed at adjusted diameters. Having adjusted said device to the proper size, it is placed upon the pie and forced downwardly, whereupon the flange 7 will trim off the surplus dough, and at the same time the flange or ring 4 will force the two crusts together and crimp their margins. It will be observed that the corrugations perform a plurality of functions, not only acting as cutters, but also as interlocking means for 70 the ends of the ring. In addition to this the corrugations permit the ready bending of the ring so as to permit its expansion and contraction. It will be evident that the device is exceedingly simple and avoids entirely the 75 necessity of turning the pie during the crimping and pressing operations.

From the foregoing it is thought that the construction, operation, and many advantages of the herein-described invention 80 will be apparent to those skilled in the art without further description, and it will be understood that various changes in the size, shape, proportion, and minor details of construction may be resorted to without departing from the spirit or sacrificing any of the 85 advantages of the invention.

Having thus fully described my invention, what I claim as new, and desire to secure by Letters Patent, is—

1. A device of the class described, comprising an expansile and contractile compressing or crimping ring.
2. A device of the class described comprising an expansile and contractile compressing or crimping and cutting ring.
3. A device of the class described, comprising an expansile and contractile compressing or crimping ring having its end portions 95 slidably overlapped.
4. A device of the class described, comprising an expansile and contractile corrugated compressing or crimping ring having its end portions slidably overlapped, the corrugations of said end portions adjustably interlocking.
5. A device of the class described, comprising an expansile and contractile ring com-

posed of angularly-disposed annular flanges having slidably-overlapped end portions, one of said flanges constituting a compressing member, and the other a trimming or cutting member.

6. A device of the class described, comprising an expansile and contractile corrugated crimping-ring having slidably-overlapped end portions, the corrugations of said end portions adjustably interfitting, a depending annular flange carried by the crimping-ring and having slidably-overlapped ends, and handle elements carried by the end portions and movable toward and from each other to contract or expand the device.

7. A device of the class described, comprising an expansile and contractile com-

pressing-ring having slidably-overlapped end portions, an annular depending flange having slidably-overlapped end portions forming an ²⁰ expansile and contractile cutting element, a handle carried by the outer end, and another handle carried by an intermediate portion of the device and movable toward and from the first-mentioned handle to contract or expand ²⁵ said device.

In testimony that I claim the foregoing as my own I have hereto affixed my signature in the presence of two witnesses.

WILLIAM ALLEN BEAMER.
